(57) **CLAIM**

The ornamental design for a cordless grass shear, as shown and described.

DESCRIPTION

FIG. 1 is a perspective view of the cordless grass shear showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 2; and,

FIG. 10 is an enlarged view of portion 10 in FIG. 2.

The dash broken lines shown in the drawings depict portions of the cordless grass shear that form no part of the claimed design. The dash-dot broken lines on FIGS. 2, 9 and 10 are provided to define the enlargement regions in each and form no part of the claimed design.
